US0D1077961S

(12) **United States Design Patent** (10) **Patent No.:** **US D1,077,961 S**
(45) **Date of Patent:** **** Jun. 3, 2025**

(54) **INFLATABLE BOUNCE HOUSE**

(71) Applicant: **Hong Kong Honchang Technology Co., Limited**, Hong Kong (CN)

(72) Inventor: **Xueying Ji**, Hong Kong (CN)

(**) Term: **15 Years**

(21) Appl. No.: **29/879,326**

(22) Filed: **Jul. 6, 2023**

(30) **Foreign Application Priority Data**

Feb. 8, 2023 (CN) 202330039840.9

(51) **LOC (15) Cl.** **21-03**

(52) **U.S. Cl.**

USPC **D21/818**; D21/835

(58) **Field of Classification Search**

USPC D21/811, 814, 815, 816, 818, 819, 820, D21/826, 835
CPC A63G 31/12; A63G 31/007; A63G 21/00; A63G 31/00; A63G 33/00; A63G 2200/00; A63G 3/02; A63H 3/06; E04H 15/20; E04H 2015/201; A63B 2225/62; A63B 2225/60

(57) **CLAIM**

The ornamental design for an inflatable bounce house as shown and described.

DESCRIPTION

FIG. 1 is a perspective view of an inflatable bounce house showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view showing the inflatable bounce house in use.

The dash-dash broken lines depict the environment and form no part of the claimed design.

1 Claim, 9 Drawing Sheets
